HYDRAULIC ANTICIPATOR FOR VARIABLE PITCH PROPELLERS

Thomas B. Rhines, Glastonbury, and Walter Gerstenberger, Stratford, Conn., assignors to United Aircraft Corporation, East Hartford, Conn., a corporation of Delaware

Application May 12, 1949, Serial No. 92,902

11 Claims. (Cl. 170—160.14)

1

This invention relates to an improved control mechanism and particularly to speed control mechanism for prime movers such as turbines.

It is an object of this invention to provide an anticipating speed control responsive to speed acceleration.

It is a further object to provide mechanism which will, upon acceleration, bias a speed responsive control to produce a speed correction greater than would be produced by the speed responsive control alone due to a change in speed.

A still further object is to superimpose on a speed responsive governor control of a controllable pitch propeller a temporary biasing of the governor by mechanism responsive to changing propeller speeds.

Other objects and advantages will be apparent from the attached specification and claims and from the accompanying drawings which show a schematic diagram of the improved control mechanism.

In engines or engine and propeller combinations having large dynamic inertias such as would be present in a rapidly rotating turbine it has been found that the inertia is so large in comparison with the power being absorbed by the propeller that if any material variation in speed takes place such a large change in pitch is required before sufficient load can be imposed by the propeller to return the speed to the "on-speed" datum that severe hunting takes place. That is, by the time the propeller pitch has changed sufficiently to return the speed to "on-speed," the load has been changed so much and so long that it cannot be again corrected before the turbine has considerably over-shot the selected speed. The propeller is thus never able to keep up with the varying speed and the severe hunting results. This is true even where attempts are made to compensate the governors which usually amounts only to slowing up the pitch changing speed during sudden pitch changes and permitting a gradual approach to "on-speed" condition without a corresponding or continuous pitch change. Such a device would be slower to apply a correction force.

By our invention we have utilized a well known speed responsive governor controlling a controllable pitch propeller and have superimposed on the governor control a biasing mechanism responsive to speed changes or accelerations of the propeller or turbine so as to increase the correcting pitch change during the time the propeller is accelerating. For instance, if the propeller speed

2

starts to increase from an "on-speed" condition the acceleration or rate of change in speed will bias the governor to increase the propeller pitch even before the governor changes its speed sufficiently to materially change propeller pitch and will continue to assist the governor in its correcting pitch change effect as long as the acceleration continues. After the propeller pitch has been increased sufficiently to stop any further increase in speed and while the speed is still above the selected speed and the governor consequently is still calling for an increase in pitch, a decrease in propeller speed (negative acceleration) will bias the governor in the opposite direction, i. e., toward producing a reduction in pitch. This action opposes, and may overcome, the governor's tendency to cause an increase in pitch because of the overspeed and may even actually cause a reduction in pitch before the propeller reaches the selected speed, to thus prevent hunting.

As shown in the drawing, an engine 10 drives a governor, shown generally at 12, and a controllable pitch propeller, shown generally at 14, at a speed proportional to the engine speed. The propeller shown is of the hydraulically actuated type and the actuating fluid therefor is supplied from any suitable source. In the selected embodiment, it is obtained from an engine driven pump 16. Hydraulic actuating fluid is withdrawn by pump 16 from a sump or storage tank 18 delivered to a pressure regulating and relief valve generally indicated at 20 and then conducted through conduit 22 to a relief valve 24 and a governor actuated pilot valve 26. The pilot valve directs the hydraulic fluid under pressure selectively through conduits 28 or 30 to one side or the other of the pitch changing motor of the controllable pitch propeller 14. The relief valve 24 is the well known type in which pressure above a preselected value will actuate plunger 32 to connect pressure line 22 with sump 18 through drain line 34 to relieve any excess pressure in line 22. Conduit 28 is connected to a chamber at the rear side of plunger 32 to apply pressure fluid to back up the relief valve while the propeller is increasing its pitch so as to assure sufficient pressure in the pitch changing mechanism to overcome the pitch reducing centrifugal twisting moment and assure pitch increasing action.

The governor selected for illustration is the well known centrifugal flyweight type in which flyweights 36 are balanced against a speeder spring 38 which may be adjusted in the usual

manner by means of an adjustable abutment 40 to select the governor speed setting. The governor is driven at a fixed ratio of the propeller speed through gears 42 and 44 fixed respectively to the governor flyweight shaft 46 and engine or propeller shaft 48.

The control and relief valve 20 is not necessary for the governor control just described but is utilized in connection with the biasing mechanism forming the subject matter of this invention and will be later described in connection therewith.

The mechanism thus far described is the well known constant speed control for hydraulically actuated controllable pitch propellers. The mechanism about to be described comprises a device for temporarily biasing that control to provide a quicker and larger propeller response upon a speed acceleration in either direction from the selected speed and a reduction in the pitch changing effect of the governor upon acceleration toward that selected speed. In the embodiment shown the bias is provided by mechanism responsive to a change in a pressure differential which in turn varies with changes in propeller or engine speed. The pressure differential responsive mechanism has a bleed connection which permits it to return to a no-bias or centered condition upon cessation of speed acceleration.

Any suitable mechanism may be utilized for producing the pressure differential and in the embodiment chosen to illustrate this invention, a venturi indicated generally at 50 and having a throat 52 and runs 54 and 56 has been utilized. Fluid, preferably hydraulic fluid, is fed by a substantially constant displacement pump, such as a gear pump 16, driven at a fixed ratio of the engine or propeller speed, through the venturi, in order to produce the pressure differential varying with propeller speed. It is a well known fact that this pressure differential which is measured as a difference in static pressure varies substantially as the square of the velocity. There is an additional feature which, while not material in the usual construction, does assist the biasing action in the correct direction to reduce hunting. This action is caused by the inertia of the oil in the line 30. An acceleration tending to increase the velocity of the oil would create a temporary pressure surge in run 54 and likewise an acceleration tending to decrease the velocity (negative acceleration) would cause a temporary pressure drop in run 54 which pressure surges or drops would not be entirely reflected in the pressure at the throat 52.

In order to better control the flow through the venturi and also in order to utilize the same pump and fluid for the governor and propeller actuating-fluid, a pressure regulating control and relief valve 20 is inserted in the line between the venturi and the propeller governor and is provided with a drain line 58 leading to the sump. The purpose of valve 20 is to maintain a constant pressure in the run 56 and does this by relieving the pressure, through line 58, in the event that it exceeds a predetermined value. Valve 20 comprises a plunger 60 adapted to receive pressure on one side to move it in one direction and spring biased by spring 62 to move it in the other direction. When the pressure in run 56 reaches a predetermined value plunger 60 will be moved to withdraw plunger 64 from passage 66 thereby opening passage 66 connecting run 56 with conduit 22 and the propeller governor. If the pres-

sure in run 56 exceeds a predetermined value plunger 60 will be moved further to the left removing plunger 64 from passage 70 thus spilling fluid into drain line 58 and relieving the pressure in run 56.

The pressure differential created by the venturi 50 is utilized to operate a valve 97 which will control the flow of fluid to and from a governor biasing mechanism indicated generally at 72. The valve operating mechanism comprises generally two chambers indicated generally at 74 and 76 with pistons or partitions therein movable by the pressure differential. The piston in chamber 76 is shown as combining both the piston and the valve in a single unit.

Chamber 74 has a connection 78 at one end thereof with the run 54 of the venturi and has a connection 80 at the other end thereof connecting chamber 74 with one end of chamber 76. A piston or partition 82 separates connections 78 and 80 in chamber 74 and is spring pressed toward the higher pressure side by a spring 84.

The throat 52 of the venturi is connected, by a line 86, with chamber 76 at the end opposite its connection with chamber 74. A movable piston or partition 88 in chamber 76 separates connections 88 and 86 and is spring centered in the chamber by opposed springs 90 and 92. The centered position of piston 88 and the valve carried thereby may be adjusted by means of adjusting screws 94. The areas at the opposite ends of piston 88 are connected by means of a bleed orifice 96 arranged, in the embodiment shown, in the piston itself.

The piston 88 is operatively connected with a valve, indicated generally at 97 in the embodiment shown, lands 98 and 100 cooperating with ports 102 and 104 respectively which ports in turn are connected by suitable conduits with opposite sides of a piston 106 secured to an extension of pilot valve 26 and adapted to reciprocate in a suitable cylinder.

Fluid from any suitable source may be led to valve 97 in chamber 76 and in the embodiment selected is shown as a pump driven from engine shaft 48 by suitable gearing and delivering pressure fluid from a sump 110 through conduit 112 to chamber 114 located between lands 98 and 100. The areas 116 and 118 on the opposite sides of lands 98 and 100 respectively are connected with drain lines leading to the sump 110.

The valve has been shown as having negative lap i. e. the lands do not quite cover the ports so that fluid continuously drains from the pressure to the drain side and the pressure on both sides of piston 106 is maintained equal. With the negative lap feature small movements of the valve 97 would create a pressure difference on opposite sides of the piston 106 which pressure difference would depend upon the extent of movement of the valve. If the valve moves far enough so that one of the lands will completely block one of the ports 102 or 104 from the drain lines then the movement of piston 106 will continue as long as the drain port is blocked and will depend upon the volume of oil being delivered through the port 102 or 104 opened to pressure. By a suitable selection of the quantity of negative lap it is possible to keep the opposite sides of piston 106 connected with the drain during normal operation of the governor thus permitting substantially free movement of the pilot valve by the governor weights, subject, of course, only to the pressure bias created by pressure differences on opposite sides of the piston 106. Upon excessive

acceleration, however, with properly selected negative lap it is possible to continuously move the governor pilot valve (within the mechanical limits of motion) in the proper direction to correct or limit the acceleration as long as the excessive acceleration exists.

Valve 97 has been shown as provided with a sleeve 129 which may be continuously rotated so it will reduce the friction between valve 97 and the sleeve 120, the valve itself being held against rotation by means of the centering springs 99 and 92. From the mechanism above described it will be apparent that as long as the pressure differential between the throat and run 52, 54, of the venturi remain constant that valve 97 will remain centered and have substantially no effect on the governor pilot valve. However, when an acceleration tending to increase the engine speed takes place the volume of oil delivered by pump 16 increases thus increasing the pressure differential. This change in pressure differential can be considered as either an increase in the pressure in run 54 or a reduction in pressure in throat 52 or both. The essential fact is that an increase of velocity through the venturi will produce an increase in the pressure differential. An increase in the pressure in run 54 will increase the pressure under free floating piston 82 and move it upward as seen in the figure until it is balanced by the pressure of spring 84 and the hydraulic pressure acting on top of the piston. This piston motion causes a displacement of fluid from the top of the piston through conduit 80 to the top of piston 88. This displaced fluid flowing into chamber 76 above piston 88 results in a downward movement of that piston thus opening port 104 to the pressure from line 112 and thus increasing the pressure under piston 106 and biasing pilot valve 26 upward to thereby increase the propeller pitch and incidentally assist the governor flyweights 36 in that operation assuming that the acceleration started from an "on-speed" position. Assuming however that the increase in speed started from a speed below the selected or "on-speed" condition the flyweights 36 would then be rotating at less than selected speed and the pilot valve 26 would be in a lowered position endeavoring to decrease propeller pitch. The increase in pressure differential resulting from the increase in speed from the under speed condition would act on the piston 106 in the same manner as described above tending to bias the pilot valve 26 upward, but in this case it would be opposing the action of the flyweights thus tending to prevent or reduce any over control and its resultant hunting.

In the event of a negative acceleration and its resultant decrease in pressure differential the reverse action would take place in that the relative reduction of pressure in line 78 would permit movement of piston 82 downward under the effect of spring 84 and the pressure on top of the piston thus reducing the pressure on top of the piston 82. This reduced pressure would be transmitted through line 80 to the top of piston 88 and because the pressure in the throat 52 would reduce less than the pressure in the run 54 an unbalanced condition would result with the pressure below piston 88 being greater than the pressure above. This would result in a movement of valve 97 to increase the pressure above piston 106 and bias the pilot valve downwardly thus tending to reduce the propeller pitch and oppose the negative acceleration.

As long as the propeller speed is changing the

pressure differential between the throat and run of the venturi is changing and acts to maintain an unbalanced condition on piston 88. However, when a uniform or constant speed is attained the pressure difference, if any still remains, on opposite sides of piston 88 is bled through restricted orifice 96 to equalize the pressures and permit the valve to be returned to centered position under the influence of opposed springs 99.

For the purpose of explanation a pressure rise or decrease has been assumed in run 54. With a construction as shown, utilizing a pressure regulating valve 20, the pressure change in run 54 may be quite small and the major change may take place in the venturi throat, being a decrease in pressure upon increases in speed and an increase in pressure upon a decrease in speed. However, the change in pressure differential is the important consideration and the mechanism will operate in substantially the same manner whether the change is considered as a change in the pressure in run 54 or throat 52. It should be noted also that although a valve such as 20 is desirable, it is not essential as a pressure differential could be obtained without that valve.

It is to be understood that the invention is not limited to the specific embodiment herein illustrated and described, but may be used in other ways without departure from its spirit.

We claim:

1. Speed control means having a speed responsive governor and governor biasing means, means responsive to changes in the controlled speed for temporarily actuating said biasing means comprising, means for creating a pressure differential varying with the governed speed, a chamber having a movable partition therein, means applying changes in the pressure differential to said partition, a bleed connecting the space at opposite sides of said partition to gradually equalize any pressure difference on opposite sides of said partition, means returning said partition to a predetermined central position upon equalization of said pressure differences, and means controlled by said partition for controlling the operation of said governor biasing means.

2. Means for temporarily biasing a speed governor in accordance with the rate of speed change comprising, means creating a pressure differential varying with the governed speed, two chambers connected in series in a circuit, spaced connections to each chamber forming a part of the circuit, a movable partition in one chamber separating the connections to said one chamber, the space at the opposite sides of said partition being connected by a restricted orifice, resilient means centering said partition, a movable partition in the other chamber separating the connections to said other chamber, resilient means urging said last mentioned partition in one direction, means connecting said spaced connections with said pressure differential creating means to apply said pressure differential to said last mentioned partition to oppose said last mentioned resilient means a motor for temporarily biasing said governor, and motor control means movable by said first mentioned partition for controlling the operation of said motor.

3. Means for temporarily biasing a speed governor in accordance with the rate of speed change comprising means creating a pressure differential varying with the governed speed, two chambers connected in series across said differential, a movable partition in one chamber separating the connections to said one chamber, a re-

stricted orifice connecting opposite sides of said partition, opposed resilient means centering said partition, a movable partition in the other chamber separating the connections to said other chamber and including resilient means balancing said last named partition against pressure acting thereon, a motor for temporarily biasing said governor, and motor control means movable by said first mentioned partition for controlling the operation of said motor.

4. Means for controlling the speed of a prime mover by controlling the load imposed thereon comprising means creating a pressure differential varying in accordance with changes in the speed of the prime mover, a first chamber having a movable partition therein, means connecting said chamber at one side of its partition with the high side of said pressure differential, resilient means urging said partition against said pressure, a second chamber having a movable partition and a restricted orifice across said partition, means centering said last mentioned partition, means connecting said first chamber at the other side of its partition with said second chamber at one side of its partition, means connecting said second chamber at the other side of its partition with the low side of said pressure differential, means connecting the movable partition of said second chamber with a valve for moving the same, a speed responsive governor controlling said load, and a motor controlled by said valve for temporarily biasing said governor.

5. Means for temporarily biasing a speed governor in accordance with the rate of speed change of the governed speed in anticipation of the resulting changed speed comprising means creating a pressure differential varying in accordance with changes in the governed speed, two otherwise closed chambers connected in series across said pressure differential, a movable partition in one chamber separating the two connections to said one chamber and having a restricted bleed orifice connecting opposite sides thereof, resilient means centering said partition in said one chamber, a partition in the other chamber separating the two connections to said other chamber and resilient means balancing the partition in said other chamber against pressure acting thereon, whereby accelerations in speed will increase the pressure differential and move both partitions during the acceleration, and a constant speed following an acceleration will result in a return of the centered partition to its centered position as the pressure on opposite sides is equalized through its restricted orifice and will result in a new position of the balanced partition, motor control means movable by said orificed partition, a motor biasing said governor and controlled by said control means whereby said governor is biased in proportion to the rate and duration of said acceleration.

6. Means for controlling the speed of a prime mover driving a controllable pitch propeller by varying the load imposed by the propeller comprising, a propeller having pitch changing means, a speed responsive governor operatively connected with and controlling said pitch changing means, means for temporarily biasing said governor in accordance with the rate of change of speed comprising, a motor for biasing said governor, and valve means connected with and controlling said motor, means for actuating said valve means comprising a positive displacement liquid pump driven at a speed proportional to the speed of said prime mover, a venturi connected with the discharge of said pump, a cylinder, a

double acting piston therein operatively connected with said valve for moving the same, a conduit connecting the throat of the venturi with one side of said piston, resilient means centering said piston, a restricted orifice between opposite sides of said piston, a chamber having a movable partition therein and connected on one side of said partition with said pump and on the other side of said partition with the opposite side of said piston, and means biasing said partition in one direction to balance the unbalanced pressure on said partition.

7. Means for controlling the speed of a prime mover by controlling the load imposed thereon comprising means producing a fluid volume flow substantially proportional to the speed of the prime mover, means creating a pressure differential varying with said volume flow, a first chamber having a first movable partition therein biased in one direction, means connecting said chamber at one side of its partition with the high side of said pressure differential to urge said partition against said bias, a second chamber having a second movable partition therein biased in opposite directions to a center position, means connecting said first chamber at the opposite side of said first partition with said second chamber at one side of said second partition, and means connecting the low side of said pressure differential with said second chamber at the opposite side of said second partition, a restricted orifice between opposite sides of said second partition, a motor control connected with said second partition for movement therewith, a speed responsive governor controlling the load on said prime mover including a motor controlled by said control for temporarily biasing said governor.

8. In a speed governing system, a speed governor having a pilot valve, a double acting piston movable in a cylinder and operatively connected with said pilot valve for movement therewith, a valve having negative lap controlling the flow of fluid to and from said piston to operate said piston, a source of pressure fluid and a drain connected with said valve, means urging said valve into a centered position in which both sides of said piston are simultaneously connected with drain, means for actuating said valve in accordance with the rate of change in the governed speed comprising means creating a pressure differential varying with the governed speed, an enclosure having two movable partitions therein dividing the space within said enclosure into two end compartments and an intermediate compartment, means connecting said end compartments across said pressure differential, a bleed line connecting the intermediate compartment with one end compartment to gradually equalize any pressure difference on opposite sides of one of said partitions and applying said pressure differential to opposite sides of said other partition, means, including means movable with said other partition, for balancing unbalanced pressures acting on said other partition, said one partition being movable by pressure differences on opposite sides thereof, centering means returning said one partition to a pre-selected position upon equalization of said pressure differences, and means connecting said one partition with said valve for actuating said valve by movement of said one partition.

9. In a speed governing system, means responsive to changes in a pressure differential varying with the governed speed comprising, means for creating said pressure differential, an en-

closed space having two movable partitions therein dividing the space into two end compartments and one intermediate compartment, means connecting said end compartments, means, including a restricted orifice, connecting one end and the intermediate compartment to gradually equalize any pressure differences on opposite sides of one partition, means moving and positioning said other partition in accordance with the value of said pressure differential, said other partition having a different position for each different pressure differential, said one partition being moved, incident to movement of said other partition, by a pressure difference on opposite sides of said one partition, resilient means operatively connected with said one partition for returning said partition to a predetermined position as the pressure on opposite sides thereof is equalized and means actuated by movement of said one partition for modifying said governing system.

10. Means for temporarily biasing a speed governor comprising a liquid pump delivering a volume of liquid varying with the governed speed, a venturi connected with the discharge of said pump, a pressure regulating valve connected with the discharge of said venturi for regulating pressure in said venturi, an enclosure defining an enclosed space, two cylinders forming a portion of said enclosure, two pistons, one in each of said cylinders, dividing said enclosed space into two end compartments and an intermediate compartment, pressure lines connecting one end compartment with the throat of said venturi, and the other end compartment with the run of said venturi, a bleed line connecting one end compartment and the intermediate compartment to gradually equalize any pressure differences on opposite sides of one of said pistons, opposed centering springs acting on said one piston, means for adjusting said springs to center said piston at a preselected center position, said one piston being movable in one of said cylinders by the difference in pressure at opposite ends thereof, lands on said one piston cooperating with ports in said cylinder to form a valve to control the flow of liquid to and from a motor to temporarily bias said governor, means connecting said valve with liquid under pressure and with a drain, means including said one piston and said bleed line for applying said pressure differential across said other piston, spring means urging said other piston in one direction and balancing said pressure differential, whereby a change in the pressure differential will move said other piston and cause a temporary movement of said one piston to operate said biasing motor, and said centering springs will return said one piston to centered position upon cessation of said change to discontinue operation of said biasing motor.

11. In combination with a turbine driven hydraulically actuated controllable pitch propeller, a speed responsive governor having a pilot valve hydraulically controlling the pitch of said propeller to maintain a substantially constant propeller speed, a hydraulically actuated motor operatively connected with said pilot valve and means for controlling said motor to assist said governor in moving said pilot valve to effect a pitch change to oppose changes in propeller speed away from the selected governor speed and to oppose the action of said governor on said pilot valve upon changes in speed toward said selected speed, said motor controlling means comprising a valve operatively connected with said motor and having a negative lap and controlling the flow of hydraulic fluid to said motor and from said motor, a cylinder, a double acting piston in said cylinder and connected with said negative lap valve for operating said valve, adjustable spring means for centering said valve and piston, a bleed line across said piston, means, including a venturi, creating a pressure differential varying with propeller speed, a second cylinder, a spring pressed piston in said second cylinder, means connecting the opposite ends of said first cylinder with the respective opposite ends of said second cylinder, one of said connecting means including said venturi connected to provide said pressure differential in said one connecting means whereby said spring pressed piston may be subjected to said pressure differential and movement of said spring pressed piston by a change in said differential will result in a pressure difference on opposite ends of said double acting piston and a temporary movement of said double acting piston and negative lap valves from centered position and a gradual return of said negative lap valve to centered position by said centering springs, as the pressure difference on opposite ends of said double acting piston is equalized through said bleed line.
